UNITED STATES PATENT OFFICE.

ISABELLA MURRAY, OF LONEROCK, IOWA.

UNDERGARMENT.

1,190,448.

Specification of Letters Patent. Patented July 11, 1916.

Application filed January 16, 1915. Serial No. 2,627.

To all whom it may concern:

Be it known that I, ISABELLA MURRAY, a citizen of the United States, residing at Lonerock, in the county of Kossuth and State of Iowa, have invented certain new and useful Improvements in Undergarments; and I do hereby declare the following to be a full, clear, and exact description of the invention, such as will enable others skilled in the art to which it appertains to make and use the same.

My invention relates to new and useful improvements in undergarments of the union suit type and has for its primary object to provide a device of the above mentioned character which is formed of two similar parts arranged to be secured to one another after being placed in position upon the wearer by suitable fastening elements.

Another object is to provide a garment of the character described which is particularly designed for the sick inasmuch as it may be secured upon a sick person without necessitating the insertion of the limbs, body or arms in the garment, it being only necessary to place the person upon the back part of the garment, then lay the front part upon the person and secure the edges of the two sections in such manner that a complete garment is formed.

Another object is to provide a garment of the character described that is of simple construction, capable of being readily secured in position or removed and which is cheap to manufacture.

The above and additional objects are accomplished by such means as are illustrated in the accompanying drawings, described in the following specification and then more particularly pointed out in the claim.

With reference to the drawings, wherein I have illustrated the preferred embodiment of my invention as it is reduced to practice, and throughout the several views of which similar reference numerals designate corresponding parts, Figure 1 is a front elevation of my improved garment, Fig. 2 is a fragmentary horizontal sectional view showing the manner of forming a seam between the sections of the garment, Fig. 3 is a front elevation of the rear or back section of the garment, Fig. 4 is a horizontal sectional view taken on line 4—4 of Fig. 3, and Fig. 5 is a vertical sectional view of one of the

forms of the garment taken on line 5—5 of Fig. 3.

Referring to the drawings by characters of reference A designates as an entirety my improved garment that is formed of any suitable material and comprises similar sections 1 and 2 for the back and front, respectively.

The garment A is of the union type and each section consists of a body portion 3, leg portions 4, and arm portions 5. On the outer edges of the back section 1 of the garment are provided spaced button holes 6.

The front section 2 is divided on its longitudinal center as at 7 and comprises similar parts 8 and 9. The edges of the body 3 are overlapped as shown in Fig. 1 and secured to one another by means of buttons 10. In this connection it will be noted that I provide buttons 11 at spaced points along the edge of the section 2 for coöperation with the button holes 6 in the back section 1. In use should it be desired to place the garment upon a sick person, the person is placed upon the back section 1 after said section is laid flat upon the bed and the sections 8 and 9 of the front section 2 may be secured to the back section separately or secured to one another prior to the securing of the front section to the back section. The edges of the back section are bent over and secured by means of the buttons 11 to the front section as shown clearly in Fig. 5 of the drawings and thus a comparatively flat seam is formed along the edge of the garment.

It will be readily seen with reference to the foregoing description and accompanying drawings that I have provided a simple and effective undergarment which will prove of great service in hospitals and for children in that it may be readily and easily secured upon the body when in a position of repose without necessitating excessive or undue movement of the limbs or arms of the body.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor

changes in details of construction, proportion and arrangement of parts may be resorted to, when required, without sacrificing any of the advantages of my invention, 5 as claimed.

What is claimed is:—

A bifurcated undergarment comprising a two piece front section, fastening elements 10 to secure the separate parts of the front sections to one another, a front arm portion formed integrally with each part of the front section, a one-piece back section having button holes about the edges thereof,

rear arm portions formed integrally with the back sections and having button holes 15 about the edges thereof and buttons carried about the edges of the separate parts and arm portions of the front sections and arranged for coöperation with the button holes.

In testimony whereof I affix my signature in presence of two witnesses.

ISABELLA MURRAY.
